United States Patent Office

Des. 220,030
Patented Mar. 2, 1971

220,030

BOTTLE

James E. Plummer, Toledo, Ohio, assignor to Owens-Illinois, Inc., Toledo, Ohio

Filed Dec. 11, 1969, Ser. No. 20,464

Term of patent 14 years

Int. Cl. D9—01

U.S. Cl. D9—160

FIG. 1

FIG. 2

FIG. 1 is an elevational view of a bottle showing my new design, the opposite side being the same in appearance as the side shown; and

FIG. 2 is a top plan view thereof.

I claim:

The ornamental design for a bottle, substantially as shown and described.
